UNITED STATES PATENT OFFICE.

NILS E. LINDENBLAD, OF BROOKLYN, NEW YORK, ASSIGNOR TO RADIO CORPORATION OF AMERICA, A CORPORATION OF DELAWARE.

ELECTRICAL COIL.

Application filed December 27, 1921. Serial No. 525,050.

To all whom it may concern:

Be it known that I, NILS E. LINDENBLAD, a citizen of Sweden, and a resident of the borough of Brooklyn, Kings County, New York, have invented certain new and useful Improvements in Electrical Coils, of which the following is a specification accompanied by drawings.

This invention relates to high frequency inductance coils and similar apparatus. In wireless telegraphy inductance coils are used for loading the antenna and tuning or balancing various circuits connected therewith. These coils are not wound in compact relation, like low frequency coils, but are made up of a plurality of spaced turns of wire such as Litzendraht or other suitable wire or cable. It has been customary to wind the cable on porcelain rods spaced apart in such a way that a drum shape coil is produced. There are several disadvantages of such a type of inductance, chief among which are the difficulty of repairing the coil if a porcelain rod becomes broken and the liability of breaking down the insulation of the porcelain rod by the high potential, which necessarily is applied directly to the supporting rods. Furthermore, the number of turns in a coil of this kind cannot be readily increased if occasion demands as the porcelain rods are usually made no longer than necessary to support the number of turns of wire as first arranged.

It is the object of my invention to overcome these and other difficulties in high frequency inductance coils and the manner in which this is accomplished will be explained in the following specification, reference being had to the drawings in which:

Fig. 1 is an elevation of one of the train of insulators supporting the coil.

Fig. 2 is a perspective view of the inductance coil.

Fig. 3 is a perspective of one of the insulators and adjacent parts. Fig. 4 is an enlarged side view of a portion of the train of insulators shown in Fig. 1. Fig. 5 is a cross section on the line 5—5 of Fig. 4.

Referring to Fig. 1 of the drawing, the cable supports are made up of a plurality of porcelain or similar insulators 1 in the form of a cross as shown more clearly in Fig. 3. Metallic plates 2 insulated from

each other by the porcelain supports are secured between adjacent insulators by means of U bolts 3 and 4 located at right angles to each other and extending in opposite directions which pass through diagonal holes in the porcelain as shown in Figs. 4 and 5. The plates are clamped in position between the insulators by means of nuts on the ends of the bolts so that a substantially rigid train of insulators is produced and these may be added to make any desired length. Any number of trains may be arranged above each other but in the drawing I have shown only two. The two series of trains are secured at one end to rod 5 which in turn is connected to a supporting post 6. The other end of the series is connected to a similar rod 7. To hold the series of insulators in spaced relation I may interpose spacing insulators 8 and 9, as shown. Whenever these insulator connections are added the plates, such as 11, may be bent at right angles so that the U bolts of the adjacent horizontal insulators 1 may be clamped to one end and the U bolts of the insulators 8 may be clamped to the other end. Insulators 8, and the U bolts used therewith, may be of the same form as those shown in Fig. 3.

In Fig. 2 the insulator trains A A', B B', etc. are made up of individual insulators and plates as shown in Fig. 1. The preferred manner of winding the cables on the insulators is as follows:

Starting at 12 the cable is clamped against the first plate 2 as shown more clearly in Figs. 1 and 4. It is then clamped to the first plates in series B, C, D, E and F in succession. If an insulating covering is around the cable it is preferably removed at the point where it is clamped to the plates 2 so as to place the plate at the same potential as the cable at that point. After one turn is completed the cable then passes to the first lower plate of A'. The cable is then clamped in succession to the first plates of each of the other lower insulators B', C', etc. until the plate in train F' is reached. The cable then passes to the second plate in the upper insulator A and thence to all of the second plates in the other upper series. After the second turn is made the cable extends to the second series in the train A'.

B', etc., and another turn is made around the lower plates.

In this way the turns are alternately made at the top and bottom and extend inwardly 5 step by step until the last turn 16 is made.

To this last turn is connected the second terminal 17. It will be understood that all the cables are clamped to the plates located between the insulators and preferably good 10 metallic contact exists between the cables and plates. By connecting the terminal 17 to the high potential end of the antenna, or other part of the system with which it is used, the outer terminal 12 may be made to 15 have zero or only moderately high potential. Therefore, no expensive terminal insulators are required. No supporting posts are required on the inside of the insulator trains as the configuration chosen is such that none 20 are necessary. The high potential lead 17 therefore may be looped under the turns of the coil and connected to the antenna or other part of the system without high potential insulators as no strain is placed on 25 this terminal other than its own weight.

It will be seen from the construction chosen that the insulators are broken up into a plurality of short insulators with conducting plates between. Therefore, the 30 potential is distributed at spaced points throughout the insulator train. This means that each insulator is required to stand only the potential of two turns of the coil and liability of the insulator breaking down is 35 reduced to a minimum. If the insulator consisted of a unitary insulator rod with the cables clamped in spaced relation to it it would be more difficult to obtain an equal voltage distribution. For this reason the 40 prior construction consisting of vertical porcelain rods has a limit of length beyond which it is impractical to go. With my construction the coil may be made of as many turns or layers as desired. The insulators 1 can be continually added to the 45 trains with interspersed plates to any length desired and no breakdown points will be reached because in the embodiment shown each insulator has to stand the voltage of 50 two turns only.

The shapes of the insulators 2 are not material as any form may be used. I prefer however the star shaped insulator shown in Fig. 3 as it is a standard form of insulator of moderate price. The particular arrangement of coil shown in Fig. 2 is hexagonal in shape but this of course is not essential. This was given by way of example only and any configuration may be used. 60 Also additional trains and insulators may be added so as to support more than two layers in the coil, that is, each post 5, 7 may have three or more trains clamped thereto.

65 If desired, the opposite metal rods 7 may

be secured together by cables such as indicated at 18, particularly while the cables are being strung but these may be left in place afterwards, as the rods are insulated by the end insulators.

Having described my invention, what I claim is:

1. In an electrical coil, a series of separate insulators having conducting members therebetween and means for fastening said 75 coil to said conducting members.
2. In electrical coils, a series of separate insulators secured together with conducting members therebetween and having turns of the coil fastened to said members.
3. In electrical coils, a plurality of spaced turns, a plurality of separate insulators having conducting members disposed therebetween and each of said members supporting a turn of said coil.
4. In an electrical coil, a plurality of conducting turns and a plurality of separate insulators having conducting members disposed therebetween and connected to different turns of said coil.
5. In an electrical coil, a plurality of conducting turns, and a plurality of spaced trains composed of separate insulators each having conducting members disposed between said insulators and connected to different turns of said coil for supporting the turns at a plurality of points in the circumference.
6. In an electrical coil, a plurality of separate conducting turns in substantially the same plane, a plurality of supports located at different points in the periphery of said coil, said supports comprising a plurality of insulators with conducting members disposed therebetween and connected to the 100 turns of said coil.
7. In an electrical inductance, a plurality of flat coils, a support for each of said coils, each of said supports comprising a plurality of trains of separate insulators at different points in the periphery of said coils, the insulators of said trains having conducting members disposed therebetween and connected to the turns of the coils.
8. In an electrical coil, an insulator between the turns of said coil having a conducting member attached to each of its opposite sides.
9. In an electrical coil, an insulator between the turns of the coil, said insulator 120 having two holes through the center, conducting members at opposite sides of the insulator and a pair of U shaped bolts passing through said holes and fastened to said plates.
10. In an electrical coil, an insulator between the turns of the coil, said insulator having two holes at right angles to each other through the center, conducting plates at opposite sides of the insulator and a pair 130

of oppositely extending **U** bolts passing through said holes and fastened to said plates.

11. In an electrical coil, a train of insulators each having holes and adapted to support and insulate the turns of a coil, conducting plates between said insulators and **U** bolts extending through said holes in said insulators and fastened to the plates for connecting said insulators and plates into a train.
12. In an electrical coil, a train of insu-
- lators of star-shaped cross section each having holes and adapted to support and insulate the turns of a coil, conducting plates between said insulators, and a pair of **U** bolts extending through oppositely inclined diagonal holes in said insulators and fitting in the grooves formed by the extending portions of said insulators for connecting the plates and insulators to form a mechanically connected train.

NILS E. LINDENBLAD.
